(57) **CLAIM**

We claim the ornamental design for a multichannel radio, as shown and described.

DESCRIPTION

FIG. 1 is a front perspective view of a multichannel radio in accordance with the present design;

FIG. 2 is a back perspective view thereof;

FIG. 3 is a front perspective view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines in FIG. 8 are included for the purpose of illustrating a portion of the bottom that forms no part of the claimed design.
